Max Müller
by James P. Muller, attorney

UNITED STATES PATENT OFFICE.

MAX MÜLLER, OF HAMBURG, GERMANY.

FLOATING DOCK.

1,413,603.

Specification of Letters Patent. Patented Apr. 25, 1922.

Application filed October 22, 1921. Serial No. 509,768.

To all whom it may concern:

Be it known that I, MAX MÜLLER, a citizen of Germany, residing at Hamburg, Germany, have invented certain new and useful 5 Improvements in Floating Docks, of which the following is a specification.

The present invention relates to improvements in floating docks.

Floating docks of the ordinary type have 10 generally a U-shaped sectional elevation and are freely floatable. They may be used for docking vessels wherever there is a water-level of sufficient height. When free from the water ballast they can be put, also with 15 a vessel therein, alongside a quay-wall, crane, and the like, even if there is existing but a low height of water. In opposition to these advantages is the drawback that the vessels to be docked must be brought in and out 20 lengthwise, which necessitates a considerable clear space or water area in front and in the rear of the dock.

Docks of the off shore type which have an 25 L-shaped sectional elevation, permit the vessels to be brought in and out sideways. Such docks are therefore available for wharfs or dock-yards which possess but a restricted front-line facing the water. This advantage, however, is best obtained either by guiding 30 such docks from the shore by parallel-motion links whereby the said docks become stationary and disproportionately expensive, or by connecting them by a parallel-motion device to a separate lateral auxiliary pontoon 35 wherfrom results a loss or sacrifice of a great lateral clear area of the harbour.

The object of the present improvements is to produce a floating dock which combines the advantages of the above mentioned 40 docks, but avoids at the same time their drawbacks.

For this purpose the invention mainly consists in constructing only one of the two side pontoons of a floating dock throughout its 45 length with a side wall of suitable height, and in furnishing the other side pontoon but with side wall sections arranged some distance apart, preferably placed at the ends of this pontoon, in order to leave between 50 them a gap or passage through which the vessel can be floated in and out sideways.

One may also imagine the said side wall sections as a result from notching or recessing to the desired or required depth and 55 length a complete side wall of a U-shaped floating dock.

A further feature of the invention consists in properly dimensioning the breadth of the said side wall sections or the remaining tower-like end parts of the notched or recessed side wall in order that these end sections ensure in cooperation with the bottom compartments the necessary stability of the weighted floating dock at any draught.

In order that the invention may be more 65 fully understood by one skilled in the art to which it appertains, the same is now to be described in detail with reference to the accompanying sheet of drawings whereon is represented in a diagrammatic manner, as an 70 example, an embodiment of the improved floating dock, Figure 1 being a plan view and Figure 2 a perspective cross-sectional elevation on the line I—I of Fig. 1.

Similar letters of reference refer to similar parts throughout the several views.

The floating dock comprises a left hand side pontoon *a* carrying a side wall *a*¹, a right hand side pontoon *b* having a side wall *b*¹, if any, and a bottom pontoon 80 subdivided by longitudinal bulk-heads *c*¹ into several compartments *c*. In the example shown the side wall *b*¹ is of considerably less height than the side wall *a*¹; in practice it may be made to just surpass a little the 85 deck of the pontoon *b*. At the ends of the pontoon *b* or more properly of the side wall *b*¹ are erected up to the height of the wall *a*¹ tower-like structures *d* and *e* forming each 90 a continuation of the side wall pontoon *b* *b*¹ and in communication therewith.

The cross-sectional area of the towers *d* and *e* is so dimensioned that the said towers ensure in cooperation with the longitudinal compartments of the bottom pontoon a sufficient 95 stability of the weighted floating dock at any draught.

The vessels to be docked and undocked are brought in and out through the gap or indentation between the towers *d* and *e*, and 100 that in accordance with the respective length of the vessels either sideways or under an oblique angle.

As many changes might be made in the construction and relative arrangement of the 105 different parts without involving a departure from the spirit of my invention, I would have it understood that I do not limit myself to the exact description shown and described, but consider myself at liberty to 110 make such changes and alterations as fall within the scope of my invention.

I claim:

1. A floating dock having in one of its otherwise substantially equally high longitudinal walls a gap of relatively large extent 5 for the passage of a vessel in more or less broadside-on manner.
2. A floating dock comprising a bottom pontoon and two side pontoons, one of the latter being provided throughout its length 10 with a complete side wall and the other furnished with side wall sections set some distance apart to form between them a gap or passage for the vessel to be docked or undocked.
- 15 3. A floating dock comprising, a bottom pontoon subdivided into compartments by

bulkheads, a side pontoon having throughout its length a complete side wall of suitable height, and a second side pontoon provided at each end with a side tower of corresponding height. 20

4. A floating dock comprising a bottom pontoon with compartments, a side pontoon with a complete side wall thereon and a second side pontoon carrying a discontinued 25 side wall, the remaining sections of this latter being of a volume to ensure in cooperation with the bottom compartments the stability of the floating dock at any draft.

In testimony whereof I affix my signature. 30

MAX MÜLLER.
